CLAIM

The ornamental design for a bracket for adjusting the height of a shock absorber on a motorcycle as shown and described.

DESCRIPTION

FIG. 1 is a front perspective view of a bracket for adjusting the height of a shock absorber on a motorcycle, showing my new design.

FIG. 2 is a bottom perspective view of the bracket for adjusting the height of a shock absorber on a motorcycle, shown without environment.

FIG. 3 is a rear view of the bracket for adjusting the height of a shock absorber on a motorcycle, of FIG. 2.

FIG. 4 is a front view of the bracket for adjusting the height of a shock absorber on a motorcycle, of FIG. 2.

FIG. 5 is a right side view of the bracket for adjusting the height of a shock absorber on a motorcycle, of FIG. 2.

FIG. 6 is a left side view of the bracket for adjusting the height of a shock absorber on a motorcycle, of FIG. 2.

FIG. 7 is a bottom plan view of the bracket for adjusting the height of a shock absorber on a motorcycle, of FIG. 2; and, FIG. 8 is a top plan view of the bracket for adjusting the height of a shock absorber on a motorcycle, of FIG. 2.

The dash-dash broken lines in FIG. 1, showing a motorcycle component, depict environmental structure and form no part of the claimed design.

The broken lines showing a frame around FIG. 1, depict the boundaries of the environment and form no part of the claimed design.

The dash-dash broken lines on the surface of the bracket for adjusting the height of a shock absorber on a motorcycle, depict portions of the article and form no part of the claimed design.
